TRACK SANDER

Application filed March 5, 1930. Serial No. 433,363.

This invention relates to track sanders.

It is among the objects of the present invention to provide a novel and improved track sander particularly adapted for use in connection with locomotives or equivalent rolling stock.

A further object of the present invention is to provide a track sander which is operable to dispense sand by the operating fluid of the locomotive.

A further object of the present invention is to provide a track sander which may be operated by steam, compressed air or electricity.

15 Another object of the present invention is to provide a track sender including a motor for moving the sand and associated fluid means for assisting in the sand distribution.

20 A further object of the present invention is to provide in a track sander, means for utilizing the exhaust fluid of an operating motor to assist in the distribution of the sand.

25 Other objects of the present invention will be apparent from a consideration of the following specification taken in conjunction with the accompanying drawings, in which

Figure 1 is a longitudinal vertical section of one form of the present invention;

Fig. 2 is a sectional view taken on the line 2—2 of Fig. 1;

Referring more particularly to the drawings, it will be seen that the invention includes the provision of a sand box 10, from which sand is moved by a screw conveyor 11. The box 10 includes an externally threaded nipple 12, through which the conveyor extends, the operation of the conveyor being adapted to move sand from the box through the nipple 12. The conveyor 11 is provided with a central channel 13 from which radiating discharge channels 14 ex-

tend through the spiral flange of the conveyor. The channel 13 extends through the shank 15 of the conveyor and is adapted to receive compressed air which is discharged through the channels 14 to assist in breaking up the sand within the box, and to provide fluid pressure for discharging the sand therefrom. The terminal ends of the conveyor are provided with extending heads 16, which act jointly with the conveyor spirally for moving the sand and also act to break up any lumps of sand so that it may be easily conveyed by the conveyor flange. 50 55

For rotating the conveyor 11, a motor 17 is provided which is here shown to be operated by compressed air, steam, or equivalent fluid. It is obviously within the scope of the invention that the motor 17 may, if desired, be operated by electricity. For assisting in rotating the conveyor 11, a bearing coupling assembly, generally indicated by the numeral 18, is provided. The coupling 18 removably receives the shank 15 of the conveyor 11, as at 19, and has a longitudinal bore 20, which communicates with a side bore 21 to deliver fluid from the pipe 22 through the shank 15 of the conveyor to the conveyor flanges. The coupling assembly is provided with suitable ball bearings and packing glands to provide for a proper rotating connection from the motor 17 to the conveyor 10.

The whole assembly is mounted within an externally threaded sleeve 23, one end of which is arranged with a motor housing 24, while the other end is internally threaded within a substantially Y fixture 25, the opposite end of which is associated with the nipple 12 of the box 10. The leg 26 of the Y 25 is provided with a sand-discharge tube 27, which may lead to any suitable type of sand-discharging nozzle as shown. For assisting in the discharge of sand through the pipe 27, a fluid pressure supply pipe 28 is provided associated with the motor 17, whereby exhaust fluid from the motor may be admitted 80 85 90

to the pipe 27 for forcing the sand therethrough.

In the operation of the device, when compressed air is used for the motor, it will be seen that the air under pressure may be admitted through the pipe 29 to the motor, and, at the same time, through the pipe 22 for passage to the conveyor 12. The exhaust air from the motor is led through the pipe 28 to the discharge tube 27 and is thus doubly used in the discharge of sand. It will be understood, of course, that the rotation of the motor 17 effects rotation of the conveyor 41 and the sand is thus moved through the nipple 12 and drops by gravity through the leg 26 of the Y 25 and is discharged through the pipe 27.

When steam is used as the motive fluid for the motor 17, it will be understood that a separate fluid supply source will be required for the fluid supply through the conveyor, it being understood that the passage of steam therethrough would moisten the sand and cause a clogging. It will, however, be feasible to use the exhaust steam in the discharge tube 27.

From the foregoing it will readily be seen that the present invention provides a novel and improved track sander. It is obvious that the invention is not confined to the specific structural details herein set forth. In connection with the invention there may be used a conventional conveyor screw which is not provided with the means for delivering fluid pressure therethrough as herein shown and described. It is also obvious that the invention is not confined to the specific arrangement of fluid pressure supply for the motor and for the pipe 27. If desired, the motor may be operated electrically, and a separate steam or air supply may be provided for the pipe 27. Other changes, modifications, and the full use of equivalents may be resorted to without departing from the spirit or scope of the invention as outlined in the appended claims.

What is claimed is:

1. A track sander, including a sand box, a rotatable conveyor extending from said sand box, a sand conduit extending from said box and surrounding said conveyor, a fluid motor associated with said conveyor for rotating the same, and means for supplying fluid under pressure to the sand in said box, said means comprising fluid passageways in said conveyor.

2. A track sander, including a sand box, a rotatable conveyor extending from said sand box, a sand conduit extending from said box and surrounding said conveyor, a fluid motor associated with said conveyor for rotating the same, means for supplying fluid under pressure to the sand in said box, said means comprising fluid passageways in said

conveyor, and fluid pressure means for discharging sand through said conduit.

3. A track sander, including a sand box, a rotatable conveyor extending from said sand box, a sand conduit extending from said box and surrounding said conveyor, a fluid motor associated with said conveyor for rotating the same, means for supplying fluid under pressure to the sand in said box, said means comprising fluid passageways in said conveyor, and fluid pressure means for discharging sand through said conduit, said means utilizing the exhaust fluid from said motor.

4. A track sander, including a sand box, a rotatable conveyor extending from said sand box, a sand conduit extending from said box and surrounding said conveyor, a fluid motor associated with said conveyor for rotating the same, means for supplying fluid under pressure to the sand in said box, said means comprising fluid passageways in said conveyor, fluid pressure means for discharging sand through said conduit, said means utilizing the exhaust fluid from said motor, and means for delivering fluid under pressure through said conveyor to the sand in said box.

5. A track sander, including a sand box, a substantially Y-shaped sand conduit associated therewith, a spiral rotatable sand conveyor extending through said conduit into said box, a fluid motor associated with said conveyor for rotating the same, and means for delivering fluid under pressure through said conveyor to the sand in said box.

6. A track sander, including a sand box, a substantially Y-shaped sand conduit associated therewith, a spiral rotatable sand conveyor extending through said conduit into said box, a fluid motor associated with said conveyor for rotating the same, means for delivering fluid under pressure through said conveyor to the sand in said box, and means for delivering exhaust fluid from said motor to said conduit for assisting in the discharge of sand therefrom.

7. In a sander, a sand box having an outlet, a rotatable conveyor in the sand box for moving sand to the outlet, the conveyor having a fluid passageway with an outlet, and means for supplying fluid under pressure to the fluid passageway.

8. In a sander, a sand box having an outlet, a conveyor having a flange for moving sand to the outlet, the conveyor having a fluid passageway with an outlet in the flange, and means for supplying fluid under pressure to the fluid passageway.

9. In a sander, a sand box having an outlet, a conveyor having a spiral flange for moving sand to the outlet, the conveyor having a fluid passageway with an outlet in the periphery of the spiral flange, and means

for supplying fluid under pressure to the fluid passageway.

10. In a sander, a sand box having an outlet, a conveyor in the sand box for moving sand to the outlet, a conduit extending from the sand box outlet, means for supplying fluid under pressure to the sand in the sand box, said means comprising a fluid passageway in the conveyor, and fluid pressure means for discharging sand through said conduit.
